UNITED STATES PATENT OFFICE

133,221

DESIGN FOR A STOPPER

Irving W. Rice, New York, N. Y.

Application July 1, 1941, Serial No. 101,844

Term of patent 3½ years

To all whom it may concern:

Be it known that I, Irving W. Rice, a citizen of the United States, residing in the city, county, and State of New York, have invented a new, original, and ornamental Design for a Stopper, of which the following is a specification, reference being had to the accompanying drawing, forming part thereof.

Figure 1 is a front elevational view, and Figure 2 is a side elevational view of the stopper, showing my new design, the rear view of the stopper is substantially the same as the front view.

I claim:

The ornamental design for a stopper substantially as shown and described.

IRVING W. RICE.
